(57) **CLAIM**

The ornamental design for nasal airway tube, as shown and described.

DESCRIPTION

FIG. 1 is a front view of nasal airway tube in accordance with a first embodiment of our design;
FIG. 2 is rear view thereof;
FIG. 3 is top view thereof;
FIG. 4 is a bottom view thereof;
FIG. 5 is a left side view thereof;
FIG. 6 is a ride side view thereof;
FIG. 7 is a perspecitve view thereof;
FIG. 8 is a front view of nasal airway tube in accordance with a second embodiment of our design;
FIG. 9 is rear view thereof;
FIG. 10 is top view thereof;
FIG. 11 is a bottom view thereof;
FIG. 12 is a left side view thereof;
FIG. 13 is a ride side view thereof; and,
FIG. 14 is a perspecitve view thereof.
